UNITED STATES PATENT OFFICE.

JACOB LOEWENSTEIN, OF NEW YORK, N. Y.

ROOF AND FLOOR CONSTRUCTION.

1,182,695.

Specification of Letters Patent.

Patented May 9, 1916.

Application filed December 19, 1914. Serial No. 878,085.

To all whom it may concern:

Be it known that I, JACOB LOEWENSTEIN, a citizen of the United States, and a resident of New York, N. Y., have invented certain 5 Improvements in Roof and Floor Construction, of which the following is a specification.

My invention relates to the construction of floors of plastic material, such for instance as concrete or similar material preferably wholly or substantially monolithic in character, and the object of my invention is to produce an improved floor of such material with which is combined a support of 15 metal, and in some instances the use of hollow tile interspersed between the metallic supports. In the improved construction according to my invention, however, instead of employing metallic reinforcements 20 as tension members embedded in the concrete, I use metallic members solely to support the concrete and loads upon the same; the ends of such metallic members being permanently connected to metallic beams or 25 girders and the spaces between the same being either arched over by the aid of suitable forms upon which the concrete may be poured, or are filled with hollow tile serving as arched supporting means upon which 30 such concrete can be poured. These and other features of my invention are more fully described hereinafter, reference being had to the accompanying drawings, in which:

Figure 1, is a longitudinal section through a floor made in accordance with my invention; showing an edge or side view of one of the metallic supports; Fig. 2, is a similar view, the section being taken through a portion of the slab intermediate the metallic supports; Fig. 3, is a sectional view on the line 3—3, Fig. 1; Fig. 4, is a sectional view on the line 4—4, Fig. 1; Fig. 5, is a sectional view similar to Fig. 1, of a modified construction within the scope of my invention; Fig. 6, is a sectional view similar to Fig. 2, of the construction shown in Fig. 5; Fig. 7, is a cross sectional view on the line 7—7, Fig. 5; Fig. 8, is a sectional view on the line 8—8, Fig. 5, and Fig. 9, is a view illustrating a diagrammatic floor plan of a building constructed in accordance with my invention.

In constructing a floor in accordance with my invention, the columns of a building are 55 connected by metal beams or girders of suitable size in one direction only; the size of

said girders being anything desired since they will be built into one of the walls in most instances, where their depth will not be objectionable. The improved floor which I have designed is intended to be laid transversely of these beams, and the metallic supports carried thereby take the place of the steel joists. At the same time the metallic supports are placed close enough together to properly carry the loads, to act as part of the forms upon which the concrete can be poured, and further to act as a support for wire lath upon which the ceiling may be secured. Between the metallic supporting elements spaces will be provided by the use of centering means or hollow tiles for the passage of pipes, wires and other necessary features of modern building construction.

In the drawings, 1, 1, represent metallic elements supported by columns 2, which elements 1 may be in the form of I-beams, box girders or the like, and are preferably arranged longitudinally of a building. To 20 these beams or girders, transversely of the line of the same, I secure metallic members 3 which are simply metal flats, approximately five-sixteenths of an inch in thickness, or any proper thickness proportionate 25 to the other factors entering into the construction of such floor, and they may range from three to five inches in width, or any other desired width necessary for the conditions of a particular floor or roof. These 30 flats are bolted or secured by other permanent means as indicated at 4 to the beams or girders 1, and they lie in a natural curve or catenary between said beams; the lowest point of which curve or catenary is well 35 within the depth of the finished portion of the floor. Disposed between these several flats 3 and in such contact therewith as to prevent displacement thereof and also to insure non-leakage of concrete poured upon 40 the flats are a series of forms 5. The concrete 6, poured into the spaces above the flats knits with the concrete directly adjacent thereto over the forms; the whole forming a solid, homogeneous mass when final 45 setting takes place and producing a floor 50 slab that is wholly monolithic in character.

The forms upon which the concrete is placed may be of any kind or character suitable for such work. They may be made 55 of pressed up sheet metal of the desired shape and height, or they may be made of

paper, plaster board, magnesia sheets, asbestos or the like. The expense of such forms is so slight that they can be left within the body of concrete without materially enhancing the total expense of constructing a floor of this type especially as no additional centering is required to support the concrete while the same is being poured.

- 10 In filling in the mass of concrete over the flats, no concrete is permitted to pass below said flats, and hence at the high ends of said flats adjacent the beams or girders air spaces 7 will be formed which may communicate with the spaces 8 provided by the hollow arched forms between the flats by aperturing said forms at 9; thereby providing plenty of room adjacent the beams, and longitudinally alined therewith in addition to the room afforded transversely which is provided by the inner space of said forms, for the reception of pipes, wires, &c.
- 15 When the transverse flat sections 3 are set in place and fastened to the beams or girders, a structure 10 of plaster board, expanding metal or other suitable mesh wire structure may be stretched at the ceiling level and hung from said flats by means of suitable wire hangers 11. The hollow forms

- 20 disposed between the flats may be supported directly by the expanded metal or mesh wire 10 or suitable hangers 11^a carried by the flats may be arranged to support the same. In either case, there will be no necessity for providing the usual centering supports employed in casting a floor of this character, a condition which makes for considerable economy in the use of my improved construction. As the metal flats
- 25 carry the entire dead weight of the floor while the concrete is still plastic, no dead load stresses exist in the concrete. This is directly opposite to ordinary reinforced concrete construction where the concrete must
- 30 take up the dead load stresses.

In my improved construction, concrete will only be stressed when superimposed (live) load comes on the floor, and relieved when load is removed. As the live load

35 sometimes amounts to one-half of the total load on floor, and as the concrete will then only carry one-half the stresses present in the usual construction, a much cheaper concrete may be used with resulting economy

40 for my improved floor.

In lieu of the forms 5, which may be of any suitable material such as light metal, pasteboard, fiber or the like, as before described, I may employ hollow tile 12 between the flats and so dispose such tile as to have their under side flush with a surface subsequently forming the ceiling and which may serve as the finish thereof, or to provide flat tiles 12^a which are supported

45 by hangers 13 hung from or connected to

the metal flats 3; said flat tiles having flanged edges 14 which underlie and serve to support the edges of the hollow tile filling the spaces between the metal flats and supporting the upper filling of concrete.

The tile employed adjacent to the ends of the metal flats where the latter rise up over the top of the beams or girders are preferably provided with apertured side walls 15 in order to provide the spaces or air chambers paralleling the said beams or girders. After the several flats, and the forms, or tile, are put in place, the concrete may be poured over the same, and this will result in the formation of a slab having a plurality of concrete joists or beams disposed between the metal beams or girders supported by the columns; such joists or beams being thick at the central portion and tapering toward the edges of the slab along the lines 85 of the metal flats carried by said metal beams or girders, and the whole roof or floor structure being supported by said metal flats.

I claim:

1. In roof and floor construction, the combination of a pair of beams, a plurality of metallic members secured to said beams in spaced relation and suspended laterally between the same substantially at right angles to the beams and paralleling each other, said metallic members being relatively wide and thin and disposed with their widest portion in horizontal planes, a body of concrete disposed wholly above said metallic members and the beams, and filling independent of the concrete lying between said metallic members and beneath the concrete; said metallic members and the beams underlying the concrete and forming the sole support for the same.

2. In roof and floor construction, the combination of a pair of beams, a plurality of metallic members secured to said beams in spaced relation and suspended transversely between the same substantially at right angles to the beams and paralleling each other, said metallic members being relatively wide and thin and disposed with their widest portion in horizontal planes, hollow filler members disposed in the spaces between said metallic members, supporting means for said filler members, and a body of concrete disposed wholly above said beams, filler members and the thin wide metallic members, the metallic members and beams underlying the concrete and forming the sole support for the same.

3. The combination, in roof and floor construction, of a pair of beams, metallic members secured to said beams and lying transversely in catenary curves between the same, said metallic members being of flat metal relatively wide and thin and disposed with their widest portion in horizontal planes,

hollow tile disposed between said flat metallic members, means for supporting the tile from said metallic members, and a body of concrete overlying said tile and the metallic members and wholly supported by the latter.

4. In roof and floor construction, the combination of beams, thin flat metallic members secured to said beams and lying transversely between the same, said metallic members being disposed with their widest portion in horizontal planes, hollow filler members disposed between said metallic members and closing the space between the same to form a continuous closed bed or space to receive concrete, means carried by the metallic members for supporting said filler members, and a body of concrete disposed wholly above and overlying said filler members and the thin flat metallic members and supported wholly by the latter.

5. In roof and floor construction, the combination of beams, flexible metallic members connected to said beams and lying between the same, said metallic members being relatively wide and thin and disposed with their widest portion in horizontal planes, a series of flat tiles underlying said metallic members and supported therefrom, hollow tile fillers disposed between said metallic members and supported by said flat tiles, and a body of concrete overlying said hollow tile and the metallic members and supported by the latter.

In testimony whereof, I have signed my name to this specification, in the presence of two subscribing witnesses.

JACOB LOEWENSTEIN.
